UNITED STATES PATENT OFFICE

CHARLES B. TIBBETTS, OF WALPOLE, AND HAROLD L. SAWYER, OF LYNN, MASSACHUSETTS, ASSIGNORS TO UNITED SHOE MACHINERY CORPORATION, OF PATERSON, NEW JERSEY, A CORPORATION OF NEW JERSEY

COATING APPARATUS

Application filed May 9, 1924. Serial No. 712,004.

This invention relates to such coating apparatus as that employed for the pasting of linings or other portions of shoes. Such an organization is disclosed in Patent No. 1,467,343, Tibbetts, Sept. 11, 1923, in which an applying member, in the form of a grid having spaced bars or applying portions, is arranged to be reciprocated between two extreme positions—one in which it is 10 immersed in a body of adhesive contained in a receptacle, and the other in which it is so raised above the surface of the adhesive that the work to be coated may be pressed upon the applying surface. Under certain conditions, it may be difficult for the operator to 15 properly time the application of the work. For example, to relieve the operator of the burden of treadle-actuation to effect the grid-movement, it may be desirable to associate 20 power mechanism with the apparatus. This preferably acts continuously to reciprocate the grid, and under these conditions, unless the operator applies the work and removes it at the proper time, said work and the 25 operator's hands may both be plunged into the adhesive as a result of the depression of the grid below the surface. An object of the invention is to provide an improved machine by means of which the operator will 30 be relieved of the necessity for exercising care as to the time of application of the work or its correct presentation to the grid. This end is attained by the association with the spaced portions of an irregularly shaped applying 35 member and its receptacle, of a work-support located in the receptacle below the member and extending upward between the applying portions to a level below that of the operating position of the applying member but 40 above that of the adhesive in the receptacle. This at all times maintains the work above the surface of the adhesive, regardless of the position of the grid. Since the applying surface, in an effective form, is furnished by 45 curved bars, the supporting device may also

consist of correspondingly curved portions lying between the applying bars. The bars or other work-supporting portions may advantageously consist of projections from the bottom of the receptacle, being shown as carried upon a plate.

The accompanying drawing illustrates one of the forms in which the invention may be embodied. Here,

Fig. 1 shows, in perspective, a pasting apparatus with the improved work-support; and

Figs. 2 and 3 are transverse sections in which the grid appears, respectively, in its lowered and raised positions.

A pan or receptacle 10, for the paste or other adhesive to be applied, rests upon a bench or like suitable support 12. At opposite extremities of the pan, vertically perforated lugs 14 receive reciprocatory actuating rods 16, which pass downwardly through openings in the table. Carried removably upon the tops of the rods by yokes 18 and hangers 20 is an applying member or grid 22. This is made up of bars 24 situated within a rectangular frame, said bars preferably being curved along concentric circles having their center at one side of the grid. Spacing members 26 lie between the grid-bars, their upper faces being below the applying surfaces. The entire grid may, if desired, be formed integrally by casting. With the grid-bars having the contour illustrated, the work is coated along separated curved areas, determined by the spacing and form of the bars, and since there is a continuous change in the direction of extension of these areas, none of the strands of the fabric operated upon, either the warp or the weft, will receive an uninterrupted coating for any great length. Therefore, when the paste dries, the strains set up in the fabric by the natural shrinkage will be so distributed that the work will not be drawn out of shape, but

will remain flat upon the other shoe parts to which it is to adhere.

Below the table, the rods 16 pass through casings 28 and depending guide-brackets 30, 5 and below these they are connected by a cross-bar 32. Extending from one side of the bar is a pin 34, upon the outer end of which is an anti-friction roll entering a cam-groove 36 formed in the face of a disk 38 10 fast upon a shaft 40 journaled beneath the bench. Secured upon the shaft 40 is a worm-wheel 42 meshing with a worm 44 upon the shaft of a motor 46, which may be electrical, and supported in any convenient manner beneath the bench. Through the connections, 15 the motor rotates the cam-disk at a reduced speed, and imparts to the bar 32 a vertical movement, the groove being so formed that at the upper extreme of this movement there 20 is a dwell. This, transmitted through the rods 16, causes the grid to alternately occupy positions above and below the surface of the adhesive in the pan 10 and to rest for a short period in the former to give the operator time 25 to press the work upon the applying surface. After this, the grid descends to receive a fresh coating of paste, and again rises to the work-receiving position. Surrounding each rod 16, within the casing 28, is shown a spring 48, 30 which exerts its force to counterbalance the weight of the grid and actuating parts.

Extending between the bars of the grid are work-supporting portions 50, shown as occupying each of the spaces between the members 35 26 and between such members and the frame. As illustrated, they consist of bars, though series of spaced projections might be employed, and are curved in a horizontal plane similarly to the grid-bars, and in the elevated 40 or work-receiving position of said grid-bars, lie with their upper edges somewhat below the applying surface, leaving this fully effective. When the grid is depressed, the supporting bars, which rise above the surface of 45 the adhesive, also extend above the grid-bars, so that objects which may have been resting upon the latter will be held out of the adhesive. These bars 50 extend upwardly from the bottom of the pan 10 through the adhesive. 50 They may be carried by a base-plate 52 resting upon the pan, or may be cast integrally with the latter. Lugs 54, upon the upper side of the pan-bottom, are so situated that their 55 contact with the edges of the plate will position the support with its projections or bars passing accurately through the spaces in the grid, without contact with the grid-bars or members 26. As a result of the use of such a support, it will be seen that a positive guard 60 is set up against the plunging of the work or the operator's hands into the adhesive contained in the pan, and that no attention need be given as to the timing of the application of the work-pieces to the grid, since if this 65 element is not in its receiving position, the

bars 50 will present a supporting surface, and hold the work until the grid has risen to impress the adhesive which it carries upon the work. If, for any reason, as because of treadle rather than motor actuation, it is not desired to employ the work-support, it may readily be removed from the pan, and upon return will be definitely located with reference to the grid-openings by the lugs 54. If this convertibility is not desired, the cost of the 70 structure may be decreased by casting the 75 projections 50 directly upon the pan-bottom.

Having described our invention, what we claim as new and desire to secure by Letters Patent of the United States is:

1. In a coating apparatus, a receptacle for a coating substance, spaced curved applying bars movable into and out of the substance in the receptacle, and work-supporting bars in the receptacle lying between the applying 80 bars and curved to correspond to the shape of the spaces therebetween and extending upwardly to a point above the level of the coating substance in the receptacle.

2. In a coating apparatus, a receptacle for a coating substance, spaced crooked applying bars movable into and out of the coating substance in the receptacle, a base member, and projections from the base member arranged in a similarly crooked outline to extend through the spaces between the bars in their movement into the receptacle upwardly to a point above the level of the coating substance in the receptacle. 90

3. In a coating apparatus, a receptacle for a coating substance, spaced applying bars movable into and out of the coating substance in the receptacle, a plate constructed and arranged to be supported upon the bottom of the receptacle, and projections upon 100 the plate extending upwardly between the bars to a point above the level of the coating substance in the receptacle. 105

4. In a coating apparatus, a receptacle for a coating substance, a member movable into 110 and out of the coating substance in the receptacle and having applying portions spaced from each other, power mechanism for repeatedly moving the member into and out of the coating position constructed and arranged automatically to cause it to dwell in its upper portion and means extending upwardly through the spaces between the applying portions for constantly supporting the work during the immersion of the applying member by the power mechanism. 115

5. In a coating apparatus, a frame, a receptacle for a coating substance carried thereby, a grid having spaced crooked bars forming an applying surface arranged to reciprocate upon the frame into and out of the substance in the receptacle, a motor mounted upon the frame and geared to the grid to reciprocate it, and a plate lying at 125 the bottom of the receptacle and having pro- 130

jections extending upwardly into the openings of the grid to a point above the level of the coating substance in the receptacle.

In testimony whereof I, the said CHARLES B. TIBBETTS, have signed my name to this 5 specification.

CHARLES B. TIBBETTS.

In testimony whereof I, the said HAROLD L. SAWYER, have signed my name to this specification.

10 HAROLD L. SAWYER.

CERTIFICATE OF CORRECTION.

Patent No. 1,741,486.

Granted December 31, 1929, to

CHARLES B. TIBBETTS ET AL.

It is hereby certified that error appears in the printed specification of the above numbered patent requiring correction as follows: Page 2, line 117, claim 4, for the word "portion" read position; and that the said Letters Patent should be read with this correction therein that the same may conform to the record of the case in the Patent Office.

Signed and sealed this 9th day of December, A. D. 1930.

M. J. Moore,
Acting Commissioner of Patents.
